ELECTRICAL CONNECTOR

Charles E. Wade, Sturgis, Mich.

Application October 4, 1940, Serial No. 359,753

6 Claims. (Cl. 173—328)

The present invention relates to electrical connectors, and in particular provides improvements upon the structure disclosed and claimed in applicant's copending application, Serial No. 289,017, filed August 8, 1939, of which the present application is a continuation in part.

The principal objects of the present invention are to provide a device of the above-mentioned character, which is extremely simple in construction, inexpensive of manufacture, and which can be assembled and applied to the cooperating members in a ready and efficient manner; to provide such a structure comprising generally an insulating body, one or more electrical contacts received within the body, and spring means cooperating between each contact and the body to improve the holding relation between each contact and its associated terminal; to provide such a construction wherein the spring means are integral with each contact and bear directly against the wall of the associated opening in the insulating body; and to generally improve the construction and arrangement of devices of the above indicated character.

With the above, as well as other objects in view, which appear in the following description and in the appended claims, preferred but illustrative embodiments of the invention are shown in the accompanying drawing, throughout the several views of which corresponding reference characters are used to designate corresponding parts, and in which:

Figure 1 is a plan view of a connector embodying the invention;

Fig. 2 is a view in section, taken along the line 2—2 of Fig. 1; .

Fig. 3 is a view in section, taken along the line 3—3 of Fig. 1;

Fig. 4 is an exploded view in perspective, showing the several elements making up the connector;

Fig. 5 is a view in section, taken along the line 5—5 of Fig. 4; and

Fig. 6 is a developed view of a contact embodying the invention.

It will be appreciated from a complete understanding of the present invention that the improvements thereof may be embodied in connectors of widely varying constructions and specifically adapted for widely differing purposes. By way of illustration, but not of limitation, the invention is herein disclosed as being specifically designed to form a connection between a plurality of terminals carried by and projecting from the body of a vehicle headlamp assembly

and a corresponding plurality of wires. The connector may be characterized as comprising a readily graspable body, which houses one or more electric contacts, each contact being permanently secured to the end of an associated wire, and being formed to provide a receptacle to receive and resiliently grasp a corresponding terminal associated with the headlamp or other cooperating part.

Referring to the drawing, the present construction duplicates, except in the hereinafter respects, the construction disclosed and claimed in the above-identified copending application, and comprises generally an insulating body 20 of generally rectangular form, having one or more spacing lugs 22, projecting from the forward face thereof, and having an axially and radially extending rim 24 at the rear face thereof. The lugs 22 serve to prevent inadvertent short circuiting of the several contacts, in the event, for example, that the device is laid upon a flat conducting surface, and the rim 24 affords a convenient hand hold.

The body or insulator 20 is provided with a plurality of contacts 26, which may be and preferably are formed up by a suitable series of die forming operations from blanks of the form specifically shown in Fig. 6. Obviously, any desired number of contacts may be associated with the housing, depending upon the specific purpose for which the connector is designed, three such contacts being shown in the present construction. Each contact 26 comprises a pair of spaced legs 28 and 30, the outer end portions 32 and 34, respectively, whereof are notched and reversely turned to form abutments to cooperate with the hereinafter described shoulder 36 in the insulator, so as to assist in holding the contact in place therein. The legs 28 and 30 lie in spaced relation to each other and are adapted to receive between them a cooperating blade-like terminal 38. Preferably and as illustrated, each leg 28 is provided with a detent 40, which projects therefrom toward the other leg for cooperation with a corresponding detent opening 42 in the corresponding terminal 38.

The mid-portion 44 of the contact is folded upon itself to define a wire receiving groove, which grooved portion embraces an insulated part of the corresponding wire 46 leaving the based end portion 48 of the wire projecting into a smaller grooved area 50. It will be appreciated that the bared end portion may be suitably clamped, soldered, or otherwise permanent-

ly secured within the last-mentioned grooved part.

The wire receiving portion 44 of the contact is separated from the terminal receiving portion by a bridge constituted by the intermediate parts 52 of the blank, which portions lie in slightly spaced relation to each other and, as hereinafter described, cooperate with a corresponding shoulder 54 in the insulating body, so as to limit movement of the contact into the body.

The insulator 20 is provided with a series of identical openings, one being individual to each contact, and all whereof are designated generally by the reference character 58. Each opening 58 comprises a bore portion 58, which extends completely through the body of the insulator, and a cooperating bore portion 60, which extends inwardly from the back of the insulator to a point adjacent the forward surface thereof. The two bore portions 58 and 60 of each opening are separated by the previously mentioned shoulder, the marginal edge whereof is spaced inwardly from the rear face of the insulator by an amount substantially equal to the axial length of the previously described bridge portion 52 of the contact. In the present instance, each bore portion 58 is provided with a counterbore, which defines the previously identified shoulder 36, which shoulder extends completely around the corresponding bore portion.

To assist in guiding a terminal 38 into the space between the two leg portions 28 and 30 of the associated contact and to prevent the same from being inserted into the space between a reversely turned portion 32 or 34 and the adjacent wall of the corresponding portion 58, the opposite side wall of each bore portion 58 is provided with a rib 62, which, in the completely assembled position of the parts, is received in the notch between the corresponding two reversely turned end portions 32 or 34, in the relation most clearly shown in Fig. 1.

As is described in the copending application, each contact 26 is formed of spring-like material, and the reversely turned leg portions 32 and 34, in addition to engaging over the cooperating shoulder 36, yieldably constrain the legs 28 and 30 to a normal spacing less than the thickness of the cooperating terminal 38. This spring-like action is particularly effective adjacent the entering end of each contact, and in accordance with the present invention, it is proposed to provide each leg 28 and 30 with an additional spring-like element 64, which cooperates between the contact and the adjacent wall of the corresponding bore portion to yieldingly constrain the rear leg portions of each contact to a normal spacing less than the thickness of the cooperating terminal. In the present instance, the additional spring-like elements are constituted by integral fingers, which extend from the back of the blank and are reversely bent to the positions most clearly shown in Figs. 2 and 4. Preferably and as illustrated, the extreme ends 66 of the spring elements 64 are inwardly turned toward the adjacent leg surface and normally engage such leg surfaces even when no terminal is inserted into the contact.

Considering now the manner of assembling the individual contacts within the insulator 20 and the manner in which they are retained in place therein, each contact 26 may be introduced into the corresponding opening, from the rear, by slightly contracting the spacing between the reversely turned portions 32 and 34, so as to enable the spaced legs 28 and 30 to be slid into the corre-

sponding bore portion 58 and to enable the wire receiving portions 44 and 58 to be moved into the cooperating bore portion 60. As the contact is advanced into the opening, the abutments constituted by the slightly outwardly flared ends of the reversely turned portions 32 and 34 ultimately pass beyond the shoulder 36, at which time the spring-like character of the contact causes these abutments to snap to the shoulder engaging positions shown most clearly in Fig. 2. At this time, also, the bridge portion 52 occupies a position immediately adjacent the bridge or saddle 54. With this relation, the abutments at the ends of the reversely turned portions cooperate with the shoulder 36 so as to prevent withdrawal of the contact from the insulator and at the same time the bridge 52 and the shoulder 54 afford a positive limit to further inward movement of the contact into the insulator. During this movement, the reversely turned portions 32 and 34 straddle the guiding ribs 62, as will be appreciated.

The free width spacing between the rear portions of the legs 28 and 30 is such as to maintain the spring-like elements 64 at a spacing slightly in excess of the width of the cooperating part of the bore portion 58. Consequently, during the entering movement of the contact, the spring elements 64 and the rear leg portions 28 and 30 are slightly contracted towards each other to a normal spacing slightly less than the thickness of the corresponding terminal 38. As previously mentioned, the free width spacing of the reversely turned portions 32 and 34 is somewhat in excess of the width of the bore portion 58, so that when the contact is in the assembled position, the entering ends of the legs 28 and 30 are sprung to a spacing slightly less than the spacing of the associated terminal. Accordingly, when a terminal 38 is introduced into the contact, it spreads the legs 28 and 30 apart, compressing the reversely turned portions 32 and 34 and also compressing the spring-like portions 64. The legs 28 and 30 are consequently caused to yieldably but positively engage the entire terminal area, thus affording a good electrical connection and also increasing the wedging relation of the abutments relative to the shoulder 36. With the terminal 38 in the fully inserted position, also, the previously mentioned detent 40 engages within the corresponding opening 42 in the terminal, thus releasably but positively holding the terminal in place.

Although only a specific embodiment of the invention has been described it will be appreciated that various further modifications in the form, number and arrangement of the parts may be made without departing from the spirit and scope of the invention.

What is claimed is:

1. In a device of the class described, the combination of an insulating body having a pocket therein which opens through at least one face of the body and which pocket is provided with shoulder means, a contact received in said pocket and provided with a pair of integrally interconnected spaced leg portions to receive between them a terminal projected into said pocket through said opening, said contact being bodily insertable into said pocket, at least one of said leg portions having at least two integral spring elements spaced therealong in the direction of movement of said terminal, certain of said spring elements being positioned to engage behind said shoulder means when the contact is moved into the pocket during assembly of the contact and body so as to cooperate in limiting movement

of the contact relative to the body in at least one direction, both said spring elements cooperating between the contact and the wall of the pocket to bias said leg portions to a normal spacing less than the thickness of said terminal.

2. In a device of the class described, the combination of an insulating body having a pocket therein which opens through at least one face of the body and which pocket is provided with shoulder means, a contact received in said pocket and provided with a pair of integrally interconnected spaced leg portions to receive between them a terminal projected into said pocket through said opening, said contact being bodily insertable into said pocket, at least one of said leg portions having at least two integral spring elements spaced therealong in the direction of movement of said terminal, certain of said spring elements being positioned to engage behind said shoulder means when the contact is moved into the pocket during assembly of the contact and body so as to cooperate in limiting movement of the contact relative to the body in one direction; both said spring elements cooperating between the contact and the wall of the pocket to bias said leg portions to a normal spacing less than the thickness of said terminal, said contact having a wire engaging portion spaced from said leg portions, and means on said contact between said leg portions and said wire engaging portion for cooperating with the body to limit movement of the contact relative to the body in the other direction.

3. In a device of the class described, the combination of an insulating body having a pocket therein which opens through at least one face of the body and which pocket is provided with shoulder means, a contact received in said pocket and provided with a pair of integrally connected spaced blade-like legs to receive between them a blade-like terminal projected into said pocket through said opening, said contact being bodily insertable into said pocket, at least one of said legs having at least two integral spring elements provided thereon and spaced therealong in the direction of movement of said terminal, certain of said spring elements being positioned to engage behind said shoulder means when the contact is moved into the pocket during assembly of the contact and body so as to limit movement of the contact relative to the body in one direction, both said spring elements cooperating between the contact and the wall of the pocket to bias said legs to a normal spacing less than the thickness of said terminal.

4. In a device of the class described, the combination of an insulating body having a pocket therein which opens through at least one face of the body and which pocket is provided with shoulder means, a contact received in said pocket and provided with a pair of integrally connected spaced blade-like legs to receive between them a blade-like terminal projected into said pocket through said opening, said contact being bodily insertable into said pocket, at least one of said legs having at least two integral spring elements provided thereon and spaced therealong in the direction of movement of said terminal, certain

of said spring elements being positioned to engage behind said shoulder means when the contact is moved into the pocket during assembly of the contact and body so as to limit movement of the contact relative to the body in one direction, both said spring elements cooperating between the contact and the wall of the pocket to bias said legs to a normal spacing less than the thickness of said terminal, said contact having a wire engaging portion spaced from said legs, and means on said contact between said legs and said wire engaging portion for cooperating with the body to limit movement of the contact relative to the body in the other direction.

5. In a device of the class described, the combination of an insulating body member recessed to accommodate a contact and having a shoulder formed within said recess, a terminal engaging contact positioned in said recess, said contact having a terminal receptacle portion and a wire engaging portion joined together by an intermediate connecting portion, said receptacle portion being constituted by spaced blade-like legs formed to receive a blade-like terminal between them, said connecting portion being seated upon said shoulder to limit movement of the contact into said body, spring means carried by one of said legs and engaging shoulder means with which said recess is provided to permit a snap entry of the contact into the body but to prevent movement of the contact out of the body, additional means carried by said one of said legs and spaced from said first mentioned spring means in the direction of movement taken by a said blade-like terminal when inserted between said legs, said additional and first mentioned spring means cooperating between said contact and the wall of said recess to bias said legs to a normal spacing less than the thickness of said terminal.

6. In a device of the class described, the combination of an insulating body having a pocket therein, and a contact received in said pocket, said contact having wire holding and terminal receiving portions arranged side by side within said pocket, said wire holding portion being arranged to receive an end of a wire projecting into said pocket so that said wire end lies wholly within and is concealed by said pocket and said terminal portion being constituted by a pair of spaced blade-like legs arranged to receive a terminal member projected into said pocket between said legs, said contact having a connecting part between said portions and said pocket having a shoulder against which said part seats to limit movement of the contact into the pocket, at least one of said legs having a pair of spring elements carried thereby and spaced therealong in the direction of movement taken by said terminal member when projected into said pocket, one of said spring elements constituting a yielding abutment which permits snap entry of the contact into the pocket but prevents withdrawal therefrom, both of said spring elements cooperating between the wall of the pocket and the contact to bias said legs to a normal spacing less than the thickness of said terminal member.

CHARLES E. WADE.
